UNITED STATES PATENT OFFICE.

CARL H. BISSELL AND RAYMOND H. OLLEY, OF SYRACUSE, NEW YORK, ASSIGNEES TO GROUSE-HINDS COMPANY, OF SYRACUSE, NEW YORK, A CORPORATION OF NEW YORK.

ELECTRIC SWITCH FOR HEADLIGHTS.

Application filed October 15, 1919. Serial No. 330,741.

To all whom it may concern:

Be it known that we, CARL H. BISSELL and RAYMOND H. OLLEY, citizens of the United States, and residents of Syracuse, in the county of Onondaga and State of New York, have invented a certain new and useful Electric Switch for Headlights, of which the following is a specification.

This invention relates to electric switches and has for its object a particularly simple and efficient switch especially applicable for headlights used on locomotives and suburban electric trains. The invention consists in the novel features and in the combinations and constructions hereinafter set forth and claimed.

In describing this invention, reference is had to the accompanying drawings in which like characters designate corresponding parts in all the views.

Figures 1 and 2 are, respectively, a plan and an elevation of a switch embodying our invention.

Figure 3 is a vertical sectional view thereof.

Figure 4 is a plan view of the base block of the switch.

Figure 5 is a vertical sectional view partly in elevation of the switch member.

Figure 6 is an end view looking upwardly in Fig. 5.

Figures 7, 8, 9 and 10 are diagrams illustrating the relative positions of the switch contacts when the switch is in "off", "dim", "bright" and "dim", positions.

This switch comprises a movable switch member movable from "off" position to "bright" position and to a dimming position between "bright" and "off" positions and to a dimming position beyond the "bright" position, a spring tending to return the switch member toward its "off" position, and means for holding the switch member in its "off" position, its first dimming position and its "bright" position, the second dimming position located beyond the "bright" position of the switch member being unprovided with means for holding the switch member against return movement by the spring.

1 designates the base of the switch and 2 the movable switch member, the base 1 being here shown as located in a suitable conduit outlet box 3 having means as nipples 4 for connection with service wires, said base 1

being formed of suitable insulation and carrying contacts 5, 6 and 7 thereon which are in the form of spring fingers, these contacts coacting with the terminal conductor 8 of the switch member 2.

The switch member 2 is rotatably mounted within the cap 9 mounted on the box and comprises a cylindrical body 10 of insulation and a shank 11 extending upwardly through the top of the cap 9.

The terminal or conductor 8 is mounted on the periphery of the cylindrical body 10 and is of the form shown in Figs. 7, 8, 9 and 10.

This conductor 8 is of such form as to engage two of the contacts 5, 6 or 5, 7 and the blank space on the periphery of the body 10 of the switch between the ends of the terminal 8 is of sufficient width to permit two of the contacts as 6, 7 to occupy said space while one terminal as 5, Fig. 7 is engaged with the terminal 8.

The contact 5 is connected to one leg of an electric circuit 12 in which the headlight 13 is connected and the contacts 6 and 7 are connected to the other leg of such circuit 12, a resistance coil 14 being interposed between the terminal 6 and the leg of the circuit.

Thus, when the switch member 2 is in "off" position the terminals 6, 7 are off the conductor or terminal 8 of the switch member 2 and no current passes through the circuit 12 and lamp 13 therein. When the switch member is turned one step from "off" position, the terminal or conductor 8 moves into the position shown in Fig. 8 so that the contacts 5 and 6 are engaged with said conductor 8 and hence the current flows through the circuit 12 and the resistance 14 so that the headlight is dimmed.

When the switch is turned an additional step the terminal 8 is moved so that the terminals 5 and 6 are engaged with said terminal or conductor 8 and incidentally the terminal 6 so that the full current passes through the circuit 12 and lamp 13.

When the switch member is moved to a position beyond "bright" position, the terminals 5 and 6 are engaged with the conductor 8 so that the current in passing through the circuit 12 and lamp 13 also passes through the resistance 14, hence dimming the light.

In the illustrated form of my invention, the cap 9 is formed with ratcheting sur-

faces 15 and 16 and shoulders 17, 18, 19, the shoulder 17 limiting the handle of the switch member when the switch member is in "off" position and the shoulders 18 and 19 being located at the ends of the ratchet surfaces 15 and 16 to limit the movement of the handle of the switch member in the first dimming and in "bright" position.

The top is also provided with an additional shoulder 20 located beyond the shoulder 19 to limit the handle from going beyond the second dimming position, but there is no shoulder or any obstruction to prevent retrograde movement of the handle and the switch member back to the "bright" position by the spring which tends to move the switch member toward its "off" position or to the left, Fig. 1.

22 designates the spring which as here shown encircles the shank 11 of the switch member and extends into a recess 23 formed in the switch member 10 about the shank 11, the recess opening through the top face of the switch member. The spring 22 is connected at one end as its lower end to the switch member and its other end to the casing in any suitable manner.

Usually, the end portions of the end coils of the spring are extended radially relatively to the axis of the spring and lie in notches formed in the switch member 10 and in the lower face of the top wall of the cap 9.

24 is the handle of the switch member which is here shown as pivoted by a transverse pivot 25 to the outer end of the shank 11, the handle having a tooth 26 for coacting with the stops 17, 19 and the ratchet surfaces 15, 16.

40 The handle is normally pressed about its pivot to hold the tooth 26 engaged with the ratchet surfaces by the spring 27 inserted between the shank 11 and the handle and tending to press the handle downwardly about the pivot 25.

45 As here shown, the handle is formed with a fork embracing the upper end of the shank 11 and the spring extends horizontally from a socket 28 in the crotch of the fork into a socket 29 formed in the side of the shank 11.

The box 3 and cap 9 which form a casing for the switch member 1, are secured together in any suitable manner as by screws 55 or other fastening members 30 extending through flanges 31, 32 at the meeting edges of said box and cap, and preferably the base 1 of the switch is carried by the cap 9 and is secured thereto by screws 33 threading vertically through the corners of the base 1 of the switch and into the cap 9.

In operation, the motorman or engineer in turning on the headlight moves the handle 24 from "off" position toward first dimming position. At any time the light is to

be permanently dimmed as when the train is running through cities and towns, the handle is left in this dimmed position intermediate the "off" and "bright" positions and is held from returning to "off" position by the fact that the shoulder 26 on the handle is engaged with the shoulder 18.

When the headlight is to be fully "on" the handle is moved until the shoulder 26 abuts against the shoulder 19, the handle also being prevented from return toward "off" position or to the left by the fact that the shoulder 26 on the handle is engaged with the shoulder 19.

When, however, the light is to be temporarily dimmed as when crossing a road or any other place where the glare of the light is dangerous to traffic, the handle is moved into the position shown in Fig. 1 in which the shoulder 26 engages the shoulder 20 and is held by the motorman or engineer in such position until it is no longer necessary to dim the light when he releases the handle 25 and it returns automatically to "bright" position.

What we claim is:

1. In an electric switch, the combination of a switch member comprising a body movable about an axis, a conductor extending circumferentially around the body, a plurality of contacts arranged to be successively engaged by the conductor upon movement of the switch member in one direction, the conductor and the contacts being relatively arranged so that initial movement of said member engages the conductor with the first two contacts, a second movement of the body in the same direction engages the conductor and all three contacts and a third movement of the body in the same direction engages the conductor with the first two contacts only.

2. In an electric switch, the combination of a switch member comprising a body movable about an axis, a conductor extending circumferentially around the body, a plurality of contacts arranged to be engaged by the conductor upon movement of the switch member in one direction, the conductor and the contacts being relatively ar-

100 ranged so that initial movement of said member engages the conductor with the first two contacts, a second movement of said member in the same direction engages all three contacts and a third movement of said member in the same direction engages the conductor and the first two contacts only, operating means for actuating said body, said operating means comprising a spring 105 tending to return the switch member to its starting position and means tending to hold the operating means in its position occupied when the conductor of the switch member is in its first and second operated positions.

3. In an electric switch, the combination of

a body of insulation movable about an axis, a conductor extending in a circumferential direction around the body and having a widened position at its advance end, three contacts arranged to be engaged successively by the conductor by movement of the switch member in one direction, the third contact being arranged to engage the wider portion only of the conductor and means for operating the switch member.

4. A switch for headlights comprising a casing, a switch member located in the casing and formed with a recess opening through one end thereof, the switch member having a shank extending axially through the recess and being spaced apart from the walls of the recess, the shank extending through the wall of the casing, a spring coiled about the shank and extending into the recess and connected at one end to the switch member and at its other end to the casing, the casing being provided with ratchet teeth determining the positions of the switch member, and a handle mounted on the outer end of the shank and coacting with the ratchet teeth, the handle having a position beyond the end of the ratchet teeth, substantially as and for the purpose set forth.

25 5. A switch for headlights comprising a

casing, a switch member located in the casing and formed with a recess opening through one end thereof, the switch member having a shank extending axially through the recess and being spaced apart from the walls of the recess, the shank extending through the wall of the casing, a spring coiled about the shank and extending into the recess and connected at one end to the switch member and at its other end to the casing, the casing being provided with ratchet teeth determining the positions of the switch member, and a handle mounted on the outer end of the shank and coacting with the ratchet teeth, the handle having a position beyond the end of the ratchet teeth, substantially as and for the purpose described.

In testimony whereof, we have hereunto signed our names at Syracuse, in the county of Onondaga, and State of New York, this 22nd day of August, 1919.

CARL H. BISSELL.
RAYMOND H. OLLEY.
